UNITED STATES PATENT OFFICE.

GEORGE L. ANDERS, OF BOSTON, MASSACHUSETTS.

TELEPHONE.

SPECIFICATION forming part of Letters Patent No. 233,592, dated October 26, 1880.

Application filed June 21, 1880. (No model.)

To all whom it may concern:

Be it known that I, GEORGE LEE ANDERS, of Boston, county of Suffolk, State of Massachusetts, have invented an Improvement in 5 Telephones, of which the following description, in connection with the accompanying drawings, is a specification.

My invention relates to telephones, and has for its object to increase the volume of sound 10 transmitted without impairing the distinctness of articulation.

The invention is shown embodied in a magneto-telephone; and it consists chiefly in a novel construction of the diaphragm, and also 15 in the combination of the said diaphragm with the magnetic poles, whereby a greater magnetic force and novel arrangement of induction-coils may be employed to enable stronger electric impulses to be used.

20 The diaphragm consists of two plates, such as commonly used for telephonic diaphragms, the said plates being connected at their edges with a slight space between them. One of the 25 said plates is provided at its middle with an opening opposite the sound-passage of the usual mouth-piece through which the sound-waves pass.

The diaphragm is supported at the edge of the said central opening, so that the plate provided with the opening vibrates the most at 30 its edge, and in such vibration the other plate which has the greatest vibration, and may be called the "vibrating plate," being connected with the said edge, is vibrated bodily there- 35 with, at the same time vibrating in the usual manner as if its edge were rigidly held.

A diaphragm constructed on this plan is more flexible and readily vibrated than one of the usual kind, and a larger portion of the 40 mass of it is set in motion, the region of vibration not being confined to the central portion of the said diaphragm as when the edge is fixed in the usual manner, so that a magnetic field of larger extent can be utilized.

45 As herein shown, two horseshoe-magnets are used having four pole-pieces and induction-coils thereon arranged around the center of the vibrating plate, so that nearly the whole area of the said plate is affected by the said 50 magnets, a thing which would not be practicable if the plate were held motionless at its

edges in the usual manner, as the vibrations at the part above the poles of the magnet would in that case be very slight.

Figure 1 is a longitudinal section of a magneto-telephone illustrating my invention, and Fig. 2 a plan of the poles of the magnet, the position of the diaphragm being indicated in dotted lines.

The magnets *a b* are shown as horseshoe- 60 magnets, each having two pole-pieces, *c*, provided with the usual induction-coils *d*, the four poles being symmetrically arranged opposite to the diaphragm *e* and mouth-piece *f*.

The diaphragm *e* is made of two plates, one 65 of which, *g*, nearest to the poles of the magnets, may be such as used for a common diaphragm; but instead of being held at its edges, fixed to the frame-work, it is fastened to the edge of a second plate, *h*, similar to it, except 70 that it has a central opening, *i*, corresponding in shape and position to the sound-passage of the mouth-piece *f*.

The plate *h* is secured at the edges of the opening *i* to the end of the tube *m*, which forms a 75 continuation of the mouth-piece *f*. This forming the point of support upon which the diaphragm *e*, taken as a whole, vibrates, the tube *m* and connected mouth-piece *f*, being supported on a cross-bar, *n*, which may be adjustably connected with the frame-work *o* in any desired manner to adjust the position of the plate *g* relative to the poles *c*.

The plates *g h* are placed a slight distance apart, an annular ring or washer, *n*, being 80 placed between them where joined together at their edges, a space thus being formed between the said plates corresponding to the usual sound chamber or space above the usual diaphragm.

90 The two plates *g h* being free at their edges, the plate *g*, when set in vibration by the magnetic impulse or by sound-waves entering the mouth-piece *f*, is vibrated bodily, the edges of the two disks vibrating on account of the flexibility of the plate *h*. In this manner the magnetic force of the four poles may be utilized; for, although situated at a distance from the center of the plate *g*, where the vibrations are of greatest amplitude, the vibration opposite 95 the poles is, owing to the freedom of the edges of the plates *g h*, sufficient to produce the de-

sired effect, and nearly the whole mass of the plate *g* acts as a movable armature for the magnets, instead of a small area near the center thereof, as would be the case if the edges were 5 fixed as usual.

The plate *g*, besides its bodily movement, also vibrates within itself, owing to its own flexibility, and it will be seen that the flexibility of both plates is involved in the vibration 10 of the central portion of the plate *g*, the diaphragm, as a whole, thus having a much easier and more delicate movement than a diaphragm of ordinary construction.

A diaphragm of this sort is useful in other 15 instruments besides magneto-telephones, and it will be seen that the plate *h* need not be of magnetic material. The flexible plate or diaphragm *h*, fixed near its center and free to vibrate at its edges, may be used in connection 20 with a rigid plate to form an armature or vibrator to take the place of the flexible plate *g*.

When a number of pole-pieces and induction-coils thereon are employed with a single diaphragm, as herein shown, the said coils may 25 be connected in multiple arc or in series, as demanded by the exigencies of the case.

I claim—

1. An instrument comprising a plate or diaphragm supported at a suitable distance from 30 the edges, leaving these free to vibrate, a second plate or diaphragm, joined to the first-named at the edges, and devices for transmitting or reproducing sound-vibrations connected with said second plate or diaphragm, substantially as described.

35 2. The combination, with a magnet, of two plates or diaphragms connected at the edges, one supported at or near the center and the

other forming or carrying an armature to said magnet, substantially as described.

3. In a telephone, the combination, with the mouth-piece and sound-passage, of a vibrator or diaphragm consisting of two plates fastened together at their edges, the one adjacent to the mouth-piece having a central opening corresponding to the sound-passage and being at the edges of said opening attached to a fixed support, the other portions of the connected plates being free to vibrate, substantially as and for the purpose described.

4. In a magneto-telephone, a plate or diaphragm, fixed near its center and free to vibrate at its edges, and an armature attached to the said edges and adapted to be vibrated bodily, combined with a series of magnetic poles and induction-coils thereon arranged around the center of the said armature, as and for the purpose described.

5. In a telephone, the sound-passage and two plates or diaphragms, and an annular ring or washer between them at their connected edges, to form a space between the said plates, one of the said plates being provided with a central opening and connected at the edges thereof with a fixed support at the end of the sound-passage, to permit the sound-waves to pass through the said passage, and opening to and from the other one of the said plates, substantially as described.

In testimony whereof I have signed my name 70 to this specification in the presence of two subscribing witnesses.

GEORGE LEE ANDERS.
